UNITED STATES PATENT OFFICE.

JACOB RUPPEL, OF PITTSBURG, PENNSYLVANIA, ASSIGNOR TO LOUIS RUPPEL, OF PITTSBURG, PENNSYLVANIA.

TROUSERS.

No. 858,107.

Specification of Letters Patent.

Patented June 25, 1907.

Application filed March 26, 1907. Serial No. 364,575.

To all whom it may concern:

Be it known that I, JACOB RUPPEL, a subject of the Emperor of Germany, residing at Pittsburg, in the county of Allegheny and State of Pennsylvania, have invented certain new and useful Improvements in Trousers, of which the following is a specification, reference being had therein to the accompanying drawing.

10 This invention relates to trousers and pants particularly trousers for men, and the invention has for its object to provide a pair of trousers with novel means whereby the waist band of the trousers can be adjusted to fit persons of various sizes.

15 My improvement is particularly designed for ready made clothes, and aims to dispense with the altering of the trousers to fit persons who are corpulent or deformed about the waist. To this end, I have provided a pair of trousers with side slits and a waist belt, whereby the waist band of a pair of trousers can be made to snugly fit a person and present a neat appearance.

20 The detail construction entering into my improvement will be hereinafter more fully described and then specifically pointed out in the appended claims, and referring to the drawing forming part of this specification, 25 like numerals of reference designate corresponding parts throughout the several views, in which:—

25 Figure 1 is an elevation of a pair of trousers constructed in accordance with my invention, illustrating the same with a contracted waist band, Fig. 2 is a similar view illustrating the waist band of a pair of trousers expanded, and Fig. 3 is a perspective view of my improvement, illustrating a pair 30 of trousers and under drawers in dotted lines.

35 In the accompanying drawing, 1 designates the legs of a pair of trousers having a seat portion 2 and a waist band 3.

40 My invention resides in providing a substantially V-shaped cut-away portion 4 at the upper ends of the seams 5 or adjacent to the waist band 3 of the trousers. In thus cutting away the trousers upon the sides I provide a rear waist portion 6 and a front 45 waist portion 7, the latter being divided in front, as at 8, similar to an ordinary pair of trousers.

50 The outer sides of the rear waist portion 6 adjacent to the cut-away portion 4 are provided with tabs 9 carrying buckles 10. The edges of the front waist portion 7 are provided with straps 11, these straps being adjustably held in the buckles 10 whereby the opening 4 can be opened or closed any desired width.

55 The inner sides of the rear waist portion 6 of the trousers adjacent to the openings 4 are provided with two straps 12, the fixed ends of said straps being of a sufficient width, as at 14, to cover the opening 4, and preventing 60 the nether garments worn by a person from being exposed. The straps 12 constitute a belt having a conventional form of buckle 15, said belt surrounding the front part of a person's body and retaining the rear waist 65 portion 6 in position, while the front waist portion 7 is held in position by the straps 11 connecting with the buckles 10. To further retain the front waist portion 7 snugly upon a person's body, I provide the inner sides of 70 the front waist portion 7 with a plurality of straps or loops 16 through which the straps 12 of the belt are adapted to pass. The under drawers or garments 17, (see Fig. 3) are also provided with straps or loops 18 through 75 which the straps 12 of the belt pass, the straps or loops 18 serving to hold the under drawers or garments in a comfortable position upon a person's body.

80 On account of the slitting of the sides of a pair of trousers, I have found it necessary to shift the side pockets 19, said pockets being disposed at a slight angle with relation to the seams 5 of a pair of trousers.

85 From the illustration of my invention, it will be observed that the waist band of a pair of trousers can be enlarged or contracted according to the waist measurement of a person's body, and that a pair of trousers can be easily adjusted to conform to the waist of 90 either stout or thin persons.

95 The numerous advantages of my invention will be readily apparent to manufacturers of men's trousers and others skilled in the art of tailoring, and while I have herein described 100 the preferred construction of my improvement I desire it to be understood that such changes in the arrangement and minor details thereof as are permissible by the ap-

pended claims, may be resorted to without departing from the spirit and scope of the invention.

What I claim and desire to secure by Letters Patent, is:—

The combination with the trousers provided in the waist band thereof with **V**-shaped slits at the upper ends of the side-seams, tabs secured to the outer face of the trousers at one side of the slits, straps secured to the outer face of the trousers at the opposite side

of said slits and adjustably-connected to said tabs, and belt-straps secured to the inner face of the trouser waist-band having widened rear ends overlying and closing said **V**-shaped slits.

In testimony whereof I affix my signature in the presence of two witnesses.

JACOB RUPPEL.
